UNITED STATES PATENT OFFICE.

DE WITT C. HARRIS, OF FOND DU LAC, WISCONSIN, ASSIGNEE, BY MESNE ASSIGNMENTS, TO HARRIS TYPEWRITER MANUFACTURING COMPANY, OF FOND DU LAC, WISCONSIN, A CORPORATION OF WISCONSIN.

TYPE-WRITER.

1,115,069.

Specification of Letters Patent. Patented Oct. 27, 1914.

Original application filed April 15, 1912, Serial No. 690,756. Divided and this application filed March 20, 1913. Serial No. 755,583.

To all whom it may concern:

Be it known that I, DE WITT C. HARRIS, a citizen of the United States, residing at Fond du Lac, in the county of Fond du Lac 5 and State of Wisconsin, have invented certain new and useful Improvements in Type-Writers, of which the following is a specification.

The object of this invention is to provide 10 an improved key lever for typewriting machines.

In the accompanying drawings, Figure 1 is a fragmental vertical sectional view through a typewriter, illustrating an improved key lever embodying my invention, 15 Fig. 2 is a similar view, but showing a key lever of different form and dimensions.

In the drawings, the impression platen is indicated by the numeral 5, 6 being a type 20 bar pivotally mounted on a type segment 7 and arranged to normally rest upon an arcuate pad 8.

9 indicates a stationary frame which may be of any suitable form, and is mounted in 25 the main framework of the machine. A series of key levers 10, 11 are pivotally mounted upon a horizontal shaft 12 which is fixed in the frame 9. Each of the key levers is connected with one of the type bars 30 6 by a link 13, a pivoted bell-crank lever 14, and a link 15. The swinging movements of the key levers may be limited by a stop device 16 of any suitable form. The keys 17, upon the outer ends of the key levers 10, 11, 35 are usually arranged in three or more tiers, and for this purpose the key levers are made in three or more different lengths. In the present instance, I have illustrated only two lengths of key levers.

40 A key lever constructed in accordance with my invention has its rear portion bent back upon itself to form an arm 18, or in other words, the lever comprises a body portion and an arm 18 lying alongside each other 45 and integrally connected at one end. The key lever may be conveniently stamped from sheet metal. The arm 18 is pivoted upon the shaft 12, and the body of the lever, in the present instance extends beneath said shaft. 50 This arrangement provides a resiliency in the key lever which affords an elastic and agreeable touch, and eliminates objectionable stiffness in the action, this being a re-

sult which is very desirable. In order that the resiliency of the key levers may be uniform, the portions of said levers rearward of the pivot shaft 12 are made in different lengths for the different series of levers, so as to compensate for the difference in the leverage of their forward portions. Thus 55 the shortest levers have longer portions rearward of the pivot shaft than the longer levers. The forward ends of the levers are normally maintained in their uppermost position by a series of coiled springs 19, 60 each having its upper end engaging in an opening 20 in one of the key levers rearward of the pivot shaft 12, and being secured at its lower end to a suitable stationary part on the frame 9. Preferably, a plurality of openings 20 is provided in 65 each of the levers 10, 11, the springs 19 being attached to the longer key levers at respectively greater distances rearwardly from the shaft 12 than to the shorter levers. Thus 70 the springs exert the greatest pull upon the longest levers. The function of the springs 19 is to hold the key levers in their normal position and to return said key levers to such position after a depression of the levers. 75 So far as the springs tend to resist the depression of the key levers, the former would be objectionable, and this is especially true when the operator is writing fast and the key levers are being depressed by quick 80 strokes, because more force is required to move the parts of the key lever action suddenly and rapidly; and it is therefore desirable under these circumstances that the 85 least possible resistance be offered to the depression of the key levers. The present construction provides for this in the following manner: When one of the key levers is depressed sharply and rapidly, the key lever body yields downwardly away from the arm 90 18, and thus while the various parts of the key lever action are operated in the usual way to raise the type bar 6, the opening 20 in which the upper end of the spring 19 is attached does not travel upwardly to place 95 additional tension upon the spring 19, but said spring remains at substantially the same tension on account of the relative yielding movement between the body of the key lever and the arm 18. Thus when the operator is writing fast, the additional resistance 100 105

to the depression of the key levers, which would ordinarily be exerted by the springs 19 by reason of their increased tension, is eliminated.

5 I am aware that changes in proportion and arrangement of parts may be made without departing from the scope of my invention, and I therefore do not limit myself to the exact construction herein disclosed.

10 This application is a division of my prior application, Serial No. 690,756, filed April 15, 1912.

I claim as my invention:

1. In a typewriter, a key lever having two 15 portions yieldable with relation to each other, one of said portions being pivotally mounted, and the other portion extending underneath the pivot point and carrying a key.

20 2. In a typewriter, a key lever comprising two portions lying side by side and integrally connected at one end, one of said portions being pivotally mounted, and the other portion extending from the point of connection of the two portions toward and past the pivot point and carrying a key on its free end.

3. In a typewriter, a key lever having two 30 portions integrally connected together, one of said portions being fulcrumed, and the other portion lying alongside of and extending in opposite directions from the fulcrum point and being arranged to yield with relation to the first mentioned portion.

35 4. In a typewriter, a key lever comprising a body, and an arm lying alongside each other and integrally connected at one end, a shaft upon which said arm is pivoted, said body extending beneath said shaft, and a 40 key carried by the body whereby the body will yield away from said arm and said shaft when said key is struck.

5. In a typewriter, a key lever having a portion bent back upon itself to provide 45 resiliency between the body of the key lever and said portion and a fulcrum engaging the lever at a point forward of the bend therein.

6. In a typewriter, a key lever having its 50 rear portion bent back upon itself to form an arm, and a shaft upon which said arm is pivoted, the body of the lever extending be-

neath said shaft whereby resiliency is provided in the key lever.

7. In a typewriter, a key lever having its 55 rear portion bent back upon itself to form an arm, and a shaft upon which said arm is pivoted, whereby resiliency is provided between the body of the lever and said arm, and a spring attached to said lever rearwardly of said shaft, said lever being arranged to yield when struck a quick short blow to maintain the tension of said spring substantially constant.

8. In a typewriter, a shaft, a series of key 65 levers each having its rear portion bent back upon itself to form an arm, said arm being pivoted on said shaft and the body of each lever extending beneath said shaft whereby resiliency is provided between the body and 70 said arm, and a series of tension springs each attached to one of said levers rearwardly of said shaft, the body of said levers being arranged to yield downwardly away from the arms thereof when struck a quick 75 short blow, whereby the tension of said springs is maintained substantially constant.

9. In a typewriter, a shaft, and a series of key levers each comprising a body portion 80 and an arm, the arms of said levers being pivoted upon said shaft and the bodies extending beneath said shaft, said bodies being of different lengths, and the shorter bodies extending farther rearwardly from said shaft than the longer bodies, whereby uniform resilience is obtained.

10. In a typewriter, a key lever comprising a body portion and an arm yieldable with relation to each other, a key mounted 90 on the body portion, and a fulcrum engaging the arm at a point between the ends of said body portion.

11. In a typewriter, a key lever comprising a body portion and an arm lying one above the other and yieldably connected at 95 their rear ends, a key mounted on said body portion, and a fulcrum engaging said arm.

In testimony whereof I affix my signature in the presence of two witnesses.

DE WITT C. HARRIS.
